UNITED STATES PATENT OFFICE.

PURCHES MILES, OF BROOKLYN, NEW YORK.

COMBINED WIRES FOR WIRE FENCES.

SPECIFICATION forming part of Letters Patent No. 277,917, dated May 22, 1883.

Application filed September 18, 1882. (No model.)

To all whom it may concern:

Be it known that I, PURCHES MILES, of Brooklyn, in the county of Kings and State of New York, have invented certain Improvements in Combined Wires for Wire Fences, of which the following is a specification.

This invention is designed to provide a compound wire composed of two parallel wires so trussed by intermediate braces peculiarly applied as to insure greatly-increased strength and permanence to the said wires, especially as against vertical strain.

My said invention further comprises certain novel combinations of parts, whereby greatly-increased strength is given to the compound wire aforesaid, and whereby its use in connection with barbs or points formed therewith is provided for.

Figure 1 is a side view, and Fig. 2 a transverse sectional view, illustrating the principal feature of my said invention. Fig. 3 is a top view of the same. Figs. 4 and 6 are side views, representing additional features of my said invention; and Figs. 5 and 7 are vertical sectional views in planes transverse, respectively, to those of Figs. 4 and 6.

A B are two wires, placed at any distance apart that may be desired—as, for example, from one to two inches, more or less—and connected by oblique braces C, arranged in zigzag position with reference to each other, and indicated in Figs. 1, 4, and 6. These braces are formed of wire preferably of the same character and diameter as the wires A B, and have their opposite ends coiled around the said wires A and B with sufficient firmness and snugness to insure their retention in place. These braces C, arranged in zigzag fashion, as just described, and constituting oblique braces connecting the wires A B, and supporting the one of the said wires in relation with the other, provide, in combination with said wires, what may be termed a "trussed" combined wire capable of resisting great vertical strain in substantially the same manner that great strength in proportion to the weight involved is obtained by the principle of the truss embodied in bridges, trestle-work, and the like.

Ordinarily the series of oblique braces C will be made of a single piece of wire first bent to

zigzag form and then applied with its corners or angles twisted around the wires A B, as shown in the side views, Figs. 1 and 6. In order to provide barbs upon the aforesaid combined wire, the coils at the angles of the wire of which the braces C are made, and which attach the said braces to the wires A B, as just described, may be divided vertically, and the ends thus formed be drawn out and turned laterally to form sharp barbs, as shown at a in Fig. 4. Preferably, however, the said corners or angles will be drawn out and flattened without being divided, and will be cut or otherwise shaped laterally to form a point, as shown at b in Fig. 6, the result in either case being that the combined wire, constructed as aforesaid, is provided with strong and suitably-sharpened barbs, as also represented in Figs. 5 and 7.

In practice the construction shown in Fig. 6 is somewhat to be preferred, inasmuch as it affords greater strength and permanence than when the angular corners of the wire of which the oblique braces C are made are divided, as just explained with reference to Fig. 4.

When desired, the wire may be duplicated—that is to say, the wire of which the braces C are formed may comprise two wires placed side by side, with the corner or angle portions of the wire forming the braces C coiled around the two in substantially the same manner as the same are coiled around the one wire, as represented in the drawings. In like manner more than one additional strand of wire may be used, and the said strands, together with the original wire A, may be twisted. Where only one strand is used, as represented in the drawings, small semicircular bends or crimps f may be formed in the wire, in order to provide for the expansion and contraction of the wire from changes of temperature, and semicircular crimps may, when preferred, be formed in the braces C. It will be observed that by the construction and arrangement of the zigzag oblique braces the ends of the latter are either brought snugly against each other, as represented, for instance, in Fig. 1, or are actually united by the continuity of the wire of which they are formed, as represented in Fig. 6. In either case the lateral displace-

ment of the braces with reference to each other, or with reference to the wires A B, is prevented, and the one brace is enabled to directly support the other. Furthermore, inasmuch as the braces are attached to the wires A B by being wound around the same, a very firm and secure retention of the braces to the wires at the points of attachment thereto is insured. Furthermore, inasmuch as the points or barbs are formed directly upon the braces themselves and attached to the wires A B by the direct coiling of the braces upon the said wires, it follows that the barbs themselves are not only easily and cheaply formed, but are themselves secured in the most permanent manner to the compound wire.

I am aware that it has been proposed to form compound wires for wire fences by connecting two parallel wires with cross-wires placed at right angles to the parallel wires and with their ends provided with barbs and coiled around the said parallel wires; but my invention differs materially from such construction heretofore attempted, inasmuch as in the latter almost no effective provision is made for preventing the lateral displacement of the transverse wires. The said wires do not mutually support each other, and the barbs themselves are liable to be displaced by the movement of the transverse wires, thereby being liable to disarrangement. Such therefore I do not claim.

I am further aware that it has been proposed to unite certain parallel rods or barbs by zig-zag wires attached thereto by clamps or fastenings conjoined with the use of barbs or points, each of which is made separately and of a distinct and separate piece of wire; but such a construction differs essentially from my said invention, inasmuch as the same is complicated in character and liable to become injured or disarranged. Such therefore I do not claim, as it is devoid of the peculiar merits or advantages arising from the combinations embraced in my said invention; but

What I claim as my invention is—

1. A fence-wire consisting of two parallel strands connected by contiguous oblique braces bent around the rail-strands, substantially as shown.

2. A fence-wire consisting of two parallel strands connected by contiguous oblique braces formed of a continuous wire coiled or bent around the strands at intervals, substantially as shown.

3. A fence-wire consisting of two parallel strands connected by contiguous oblique braces formed of a continuous wire coiled or bent at intervals around the strands, substantially as shown, and provided at each angle with a barb.

PURCHASES MILES.
